FIG. 1

FIG. 2

FIG. 3

FIG. 4

FIG. 5

FIG. 6

FIG. 7

FIG. 8

FIG. 1 is a pictorial view of an outdoor light mounting fixture showing my inventive design;

FIG. 2 is a top view of the outdoor light mounting fixture shown in FIG. 1;

FIG. 3 is a bottom view of the outdoor light mounting fixture of FIG. 1;

FIG. 4 is a rear fragmentary elevational view of the outdoor light mounting fixture of FIG. 1;

FIG. 5 is a pictorial fragmentary view of a second embodiment of an outdoor light mounting fixture showing my inventive design;

FIG. 6 is a top view of the outdoor light mounting fixture of FIG. 5;

FIG. 7 is a bottom view of the outdoor light mounting fixture of FIG. 5; and

FIG. 8 is a rear fragmentary elevational view of the outdoor light mounting fixture of FIG. 5.

The standard is broken away in FIG. 1 to indicate indeterminate length and fragmentarily shown in FIGS. 4, 5 and 8 for convenience of illustration.

I claim:

The ornamental design for an outdoor light mounting fixture, as shown and described.
